(57) **CLAIM**

An ornamental design for a vehicle-affixable driver level indicator, as shown and described.

DESCRIPTION

FIG. 1 is a front view of a first embodiment of a vehicle-affixable driver level indicator, in accordance with the present invention;

FIG. 2 is a front view of a second embodiment of a vehicle-affixable driver level indicator, in accordance with the present invention;

FIG. 3 is an elevation view of the vehicle-affixable driver level indicator of FIG. 1 attached to a rear window of an automobile;

FIG. 4 is an elevation view of the vehicle-affixable driver level indicator of FIG. 1 attached to a rear bumper of an automobile;

FIG. 5 is a top/bottom view of a vehicle-affixable driver level indicator, in accordance with any of the above embodiments of the present invention; and,

FIG. 6 is a side view of a vehicle-affixable driver level indicator, in accordance with any of the above embodiments of the present invention.

In the drawings, the broken lines illustrate environment and form no part of the claimed design.
